CLAIM

The ornamental design for a refractometer, as shown and described.

[21] Appl. No.: 806,063

DESCRIPTION

[22] Filed: Nov. 21, 1985

FIG. 1 is a left front, top perspective view of a refractometer showing my new design;

[52] U.S. Cl. D24/17

FIG. 2 is a right side elevational view thereof; and

[58] Field of Search D24/8, 17; 356/128, 356/129, 130, 131-137; D10/46; D16/1, 15, 28; D9/418

FIG. 3 is a rear elevational view thereof.
The bottom of the design is substantially plain and unornamented.

FIG. I

FIG. 2

FIG. 3
